UNITED STATES PATENT OFFICE.

HELEN MACHOWICZ, OF BROOKLYN, NEW YORK.

SUPPORT FOR WINDOW SHADES AND CURTAINS.

Application filed February 8, 1926. Serial No. 86,884.

This invention relates to support for a window shade and curtain, and has particular reference to support capable of being shifted and adjusted with respect to a window frame to which it is attached.

The principal object of the present invention is to provide means of the indicated character for shifting a window shade and curtain, clear of a window frame opening to facilitate the cleaning of the window panes, and so that when the window sashes are opened to hold the curtains from blowing out of the window opening and thus keeping them from becoming soiled; and the said window shade and curtains being also supported in a manner to be lowered from a normal position to a convenient position for making necessary adjustments or for removing or cleaning the same without requiring the use of a step ladder or the like.

Another object of the invention is the provision of means for supporting window shades and curtains on a double window and capable of being adjusted vertically to different positions and maintained in the different adjusted position.

With the foregoing and other objects in view the invention resides in the particular provision, relative disposition, construction and operation of the parts hereinafter fully described and illustrated in the accompanying drawings, in which—

Figure 1 is an elevation showing one embodiment of the present invention applied to a window frame with the window shade and curtains shifted from a normal position, the curtains being shown in dot and dash lines.

Fig. 2 is a perspective view of the embodiment of the invention shown in Fig. 1 and showing the same detached.

Fig. 3 is a fragmentary sectional elevation, portions being broken away, the section being taken on the line 3—3 of Fig. 2.

Fig. 4 is a sectional view taken on the line 4—4 of Fig. 2, and illustrating details.

Fig. 5 illustrates a modification for adjustably supporting a plurality of window shades and the necessary curtains and the like on a double window construction.

Fig. 6 is a diagrammatic view of the embodiment of the invention shown in Fig. 5 and illustrating more clearly the manner in which the bracket supporting members are raised and lowered.

Referring now more particularly to Figs.

1 to 4 inclusive, it will be apparent that, there is shown a window frame 10 of the usual construction having vertical stiles 11 and a head rail 12. The window frame 10 is shown for the purpose of illustrating one application of the appurtenances or parts involved in the present invention which are as follows: Attached to each of the vertical stiles 11 is a guide 13; each guide 13 comprises members 14 spaced with respect to each other, and each of said members 14 has a tongue 15. The members 14 are connected together by cross pieces 16 at the opposite ends thereof respectively, and the said cross pieces 16 serve for effecting the attachment of the guide. A member 17 is associated with each of the guides 13 for sliding movement. Each member 17 has grooves 18 in the opposite side edges thereof which respectively receive the tongues 15, thus permitting the sliding movement of the member 17 and holding the same against displacement. A bracket 19 is attached to the upper end of each of the members 17, and attached to the horizontal portions of the brackets 19 is a guide 20. The guide 20 comprises members 21 spaced with respect to each other and held in the spaced relationship by cross pieces 22. Each of the members 21 has a tongue 23. A bracket supporting member 24 is associated with the guide 20. The member 24 has grooves 25 in opposite side edges thereof which respectively receive the tongues 23, thus permitting the sliding movement of the member 24 and serving also to hold the same against displacement. Any suitable means such as the means 26 for supporting a roller shade and curtains is attached to and supported by the member 24. In the illustration in Fig. 1 there is a roller shade 27 and curtains 28 are indicated in dot and dash lines.

In order to shift the member 24 and therefore the appurtenances carried by said member clear of the window frame opening there are provided in the illustrated example pull cords 29 connected respectively to the opposite ends of the member 24 as at 30, and each cord is passed through an eye 31 attached to one of the members of the guide 20 near the extremity thereof. The free end of each cord 29 has a ring 32. It will now be apparent that when a pull is exerted on the cord 29 at the right side of the window frame 10, the supporting member 24 will be slid to the right and the appurtenances car-

ried thereby will be shifted accordingly. A pull on the cord 29 at the left of the window frame will result in the supporting member 24 with its appurtenances being shifted to the left. With the arrangement shown the roller shade and curtains may be shifted clear of the window frame opening. When the roller shade and curtains are shifted to either side of the window frame opening the window panes may be easily cleaned, and when either of the sashes is in an open position the curtains will be kept from blowing out of the window opening and from becoming soiled.

In order that the shade roller and curtains may be lowered to a position within convenient reach of a person for either adjusting or removing the same there has been provided the members 17 and guides 13. In order to maintain the supporting member 24 which supports the roller shade and curtains in different positions, there is provided a holding means. The holding means in the present instance consists of a plate 33 connected to the lower end of each member 17 as at 34 by a screw bolt and nut. The plate is capable of turning about the bolt and a handle 35 attached to the plate 33 is provided for that purpose. Pairs of pins 36 extending out respectively from the members 14 provide rests at different intervals. When the plate 33 is disposed horizontally the lower edge thereof rests on a pair of the pins 36 as shown in Figs. 1 and 2 to hold the member 24 in the desired position.

It is to be understood that if desired the guide 20 and supporting member 24 with its connected parts may be used without the members 17 and their guides 13 to support a roller shade and curtains in a manner to be shifted clear of a window opening at opposite sides thereof.

In the modification shown in Figs. 5 and 6 provision is made for supporting a plurality of window roller shades 40 for movement up and down with respect to a double window frame 41. This is accomplished by providing three guides 42 attached respectively to the vertical stiles of the frame 41. Associated with each of the guides 42 is a slide block 43. Each block is held for sliding movement by virtue of tongues and grooves similar to the manner in which the members 17 are associated with their guides 13. Three pull cords 44 are connected respectively to the blocks 43 as at 45. The cords running to the side blocks are passed through an eye 46 attached to the upper end of the middle guide 42. The cord 44 attached to the middle block 43 is passed through an eye 47 attached to the guide 42 below the eye 46. The free ends of the cords 44 are tied to each other and the untied extremities are connected to a ring 48. The blocks 43 have attached thereto suitable sup-

porting brackets 49 for supporting roller shades, curtains and the like. The blocks 43 are held in different positions by means similar to the plates 33 and pins 36. By taking hold of the ring 48 it is possible to raise or lower the appurtenances at each of the window openings of the frame 41 simultaneously.

It is to be understood that the invention is not restricted to the precise arrangement of parts shown and described, as details of construction may be modified and the parts rearranged without departing from the spirit of the invention, the scope of which is limited only by the terms of the appended claims.

I claim:

1. For a window frame, bracket supporting means for supporting a roller shade and curtains, and means on which said bracket supporting means is mounted for sliding movement clear of the window frame opening.

2. For a window frame, bracket supporting means for supporting a roller shade and curtains, means on which said bracket supporting means is mounted for sliding movement clear of the window frame opening, and means for moving said bracket supporting means clear of the window frame opening.

3. For a window frame, a bracket supporting means for supporting a roller shade and curtains, means on which said bracket supporting means is mounted for movement to either side of the window frame clear of the opening in the same, and means for effecting the movement of the bracket supporting means to either side of the window frame clear of the opening therein.

4. For a window frame, a bracket supporting means for supporting a roller shade and curtains, means on which said bracket supporting means is slidably mounted for movement to either side of the window frame clear of the opening in the same, and means for effecting the sliding movement of the bracket supporting means to either side of the window frame clear of the opening therein.

5. On a window frame, a single support arranged at the head rail of the window frame, a roller shade and curtain supporting bracket on said support, a guide attached to said head rail in which said support slides, and means for sliding said support in opposite directions, said means including pull cords attached respectively to the opposite ends of said support and each pull cord passed through an eye attached to said guide.

6. In a window shade and curtain support, a slideable supporting member, and means for maintaining the supporting member in different adjusted positions, said means comprising a turnable plate connected

with the supporting member, and fixed pins on pairs of which said plate is adapted to rest.

7. On a window frame, a roller shade and curtain supporting means shiftable clear of the window frame opening to either side thereof, and means for raising and lowering said first named means.

8. On a window frame, a roller shade and curtain supporting means shiftable clear of the window frame opening to either side thereof, means for raising and lowering said first named means, and means for maintaining the first named means in different adjusted positions.

HELEN MACHOWICZ.
